United States Patent Office.

ROBERT BAXTER, OF FRENCH CAMP, CALIFORNIA.

Letters Patent No. 70,781, dated November 12, 1867.

IMPROVEMENT IN SEEDING MACHINES.

The Schedule referred to in these Letters Patent and making part of the same.

TO ALL WHOM IT MAY CONCERN:

Be it known that I, ROBERT BAXTER, of French Camp, in the county of San Joaquin, and State of California, have invented a new and useful Machine for Sowing Grain, and called Baxter's Grain-Sower, to be used in connection with gang-ploughs or cultivators; and I do hereby declare that the following is a full, clear, and exact description of the construction and operation of the same, reference being had to the annexed drawings, making a part of this specification, in which—

Figure 1 is a front elevation of the grain-sower, with the outside piece of the front part removed, the upper front piece O and middle piece F remaining, thus showing the inside of the lower part of the seed-box, (to wit, below F,) the rod B, and its prongs C, and the iron plates D and E, on the bottom and at the front side of the box; also appear the elbow G and pitman H, by which the power from the plough-wheel K is communicated to the rod B, giving it, with its prongs C, a lateral motion when the plough is in operation, the ends of the prongs being turned towards the centre of the box, and passing back and forth over the holes in the plates, the object being to keep the holes clear, and to secure a steady flow of grain thereby.

Figure 2. D shows the upper plate, which is let into the bottom of the box, so that the top part is level with the same, being (4 $\frac{1}{2}$) four and one-half inches wide, and (1 $\frac{1}{16}$) one-sixteenth of an inch thick; also are shown the ends of the prongs C, turned towards the centre of the box.

Figure 3. E shows the lower iron plate, in which, as in the upper plate, there are small holes, three-fourths of an inch in diameter, the same corresponding in size and distance with those in the upper plate. This plate, being a little shorter than the upper plate, is capable of a lateral motion, the same being effected by means of a small handle, P, (fig. 1) attached to the lower plate, thus regulating the flow of the grain.

Figure 4 presents an end view of the seed-box, and its connection with the plough; also shows the elbow G, pitman H, and iron clasp or elbow Q, (which clasps the corner of the box,) in which are set two eyes V V, which receive the ends of a gudgeon projecting either way from the elbow, thus forming a pivot, on which the elbow G works.

Figure 5 shows a cross-section of the box, including the rod B, its prongs C, the iron plates D and E, and holes therein; also S, a piece of sheet iron, which is screwed to the bottom of the box just behind the holes, and on which the grain falls, and by which it is scattered, the same tapering from the box, and being two and a half inches wide at the box, (1) one inch wide at the lower end, and (5) five inches long.

In fig. 1, L represents a cross-beam, in which the box rests when used with Baxter's gang-plough, the same being secured by bolts through the bottom of the box. N represents the end of the main beam, and M other cross-beams of said plough, to which the drawing-gear is attached. I, the irons connecting the wheel with the plough, and K the wheel.

The seed-box and machinery connecting it with plough-wheel can be easily used with any gang-plough. It is constructed of inch boards, (lighter may be used,) the end pieces being of irregular form, as by fig. 4 appears. The top part or cover of the box A is (10) ten inches in width, and secured to the back part by a hinge, and designed to be level when in position. The back part (as appears by X, cross-section, fig. 5) forms an acute angle with the top part, slanting forward, and being (8) eight inches in width or height. With the back part, the bottom piece (as appears by cross-section 7, fig. 5) forms an obtuse angle, slanting forward to front piece, and being (8) eight inches wide. The front part is composed of three pieces, (as appear in O, F, and E, cross-sections, fig. 5,) being (10) ten inches high, and its general position or line at right angles with top part or cover. The top piece O (of front side of box) is about (5) five inches wide, and is set into the end pieces, and back of the front edge thereof, about (1 $\frac{1}{2}$) one and one-half inch, leaving a shoulder at the upper front corners of the end pieces. (See Z, fig. 4.)

To the bottom part of piece O, (fig. 1 or 5,) and at right angles with it, is attached the piece F, (fig. 1 or 5,) (3) three inches in width, one-half of same (inch and one-half) extending back and the other in front of piece O, (see F, fig. 5,) and even with the front edge of the end pieces R R, fig. 1. In this piece F there are grooves, through which the prongs C pass to the bottom of the box, of sufficient width to allow a horizontal motion of the prongs over the holes in the plate D.

To the end pieces R R, and the middle pieces F, F, and S, and the bottom part, is attached the third piece,

or outside front piece, which is a plain board, of proper size to cover the front of the box within two inches of the top thereof, leaving a space of little over an inch between the piece O and the outside front piece E', (see fig. 5,) in which is placed the rod B, which is kept in place by, and plays back and forth in, grooves cut in the end pieces, said grooves being protected by nail-plate, screwed to the end of the box, in which there are like grooves. Said rod B is of iron, and one-quarter ($\frac{1}{4}$) of an inch thick, and one-fourth ($\frac{1}{4}$) of an inch wide, and long enough to connect with the elbow G, and allow a horizontal motion sufficient to carry the prongs back and forth over the holes in the plate D.

The prongs C of the rod are three-eighths by three-sixteenths of an inch, and at the end in two parts, C, fig. 2.

The rod B is operated by the wheel, through the elbow G, in the upper arm of which there is a groove, into which is received the end of the rod B, the rod being cut down on each side thereof, so as to fit into the groove of the elbow, and have two shoulders on either side of same, against which the elbow works. The other arm of the elbow G is connected, by means of a common pitman, with a pin on the wheel, about one and one-half inch from the centre thereof, the wheel thus furnishing the moving power for the rod B.

It will be seen, by examination of figs. 1 and 5, that the ends of the prongs are within the box, and close to the front side thereof, the rod and that part of the prongs C C above F, fig. 1, being outside of the box proper.

The plates D and E, (figs. 2 and 3,) placed on the inside and close to the front part of the box, are let into the bottom piece D equal to its thickness, and E underneath D equal to its thickness, in a separate groove. The upper plate D is secured in place by the front edge being let into the front piece, and screwed at its back edge to the bottom of the box. The lower plate E is shorter than the box, so as to admit of an end motion sufficient entirely to shut off the flow of grain. Both plates have holes of three-fourths inch in diameter in them, and corresponding with each other. Directly underneath the holes, in the upper plate D, are corresponding holes in the bottom part of box, through which the grain escapes, the flow of grain being controlled by moving the lower plate E, which is done by means of a handle thereto attached, (P, fig. 1.)

The wheel of the plough with which this seed-box is used should not be over (15) fifteen inches in diameter.

The length of the box is controlled by the size of the gang. The holes through which the grain escapes should each be on a line with land-side of the standards, and the pieces of sheet iron on which the grain falls should be turned or twisted towards the furrows. There should be one hole to every standard.

The object of the middle piece of the front part of the box (E, fig. 1) extending back into the interior of box is to relieve the prongs C of any over weight from the grain when the box is full.

What I claim as novel, and for which I ask Letters Patent, is—

1. The seed-box, constructed as described, and provided with a rod and prongs, so located that a part of the several prongs only is in the box, and that at the front side thereof, as and for the purpose described.

2. The elbow-lever, operated by a pin on the plough-wheel, and operating the rod with its prongs, in combination with said rod, in the manner and for the object set forth.

Stockton, March 25, 1867.

ROBERT BAXTER.
